DRIVING MECHANISM FOR PRODUCING
GYRATORY MOVEMENT

George H. Hebebrand, St. Louis, Mo.

Application May 19, 1934, Serial No. 726,597

7 Claims. (Cl. 74—86)

This application is filed to take the place of my abandoned application, Serial No. 337,806, filed February 19, 1929.

- This invention has for its general object to provide improved driving mechanism for producing gyratory movement of a suspended body, such as a sifting machine, which, in operation, will enable the sifter to be placed in movement and to gradually cease its movement after power 5 is cut off without producing an erratic movement of the sifter or a movement thereof beyond the limits of its normal zone of operation.
- In the type of driving mechanism to which my invention relates, in which a pivotally mounted weight is employed for producing the gyratory movement of the plan sifter, the prior constructions of which I am familiar have all possessed the disadvantage of producing a wide circular swinging movement of the plan sifter both in 10 starting and stopping. This is due to the fact that as the arm or other member carrying the weight is pivoted at a fixed point, the weight will start to swing outward as soon as revolution thereof is started, and as the weight is relatively quite heavy, it tends to impart a circular movement to the sifter or to cause the sifter to move in unison with it, instead of opposing its movement, throwing the plan sifter beyond its 15 normal path of movement, with the result that frequently the flexible conveying members, or "stockings", connected to the plan sifter for conveying away the flour and other products to various spouts, are torn off, and before the machine can be stopped the flour and other products 20 delivered from the plan sifter are thrown about the floor of the mill. Again, when the power is shut off and the momentum of the weight decreases, it begins to fall until it reaches a point where its movement is substantially synchronized 25 with the movement of the sifter, with the result that the rotating weight will now tend to swing the sifter in a circular path, causing it to move beyond the limits of its normal zone of movement, with the result, as in the case of 30 placing the plan sifter in operation, that the stockings are frequently torn off of the plan sifter and in some cases, the plan sifter has been thrown against posts or other objects in the mill, causing injury and considerable loss.
- Whatever the character and extent of the erratic or irregular movements of the plan sifter, more or less strain is placed on the building and there is a necessary increase in the wear of the bearing and supporting members.
- According to my invention, the plan sifter is

caused to gyrate by the movement of a weighted member which is so mounted that its point of pivotal support varies as the weight moves outward and upward in starting and likewise in its downward and inward movement in stopping, so that the action of the weight gradually increases in intensity with the speed of rotation and gradually decreases in the stopping of rotation, producing at all times a balanced regular movement of the plan sifter.

Another disadvantage incident to prior constructions is that the center of gravity of the weight has been disposed to one side of the rotating shaft on which the weight is pivotally mounted for rotation. The result is that the center of gravity of the weight is always outside of the center of gravity of the plan sifter, which is one reason why, in the stopping movement, the weight tends to carry the plan sifter around in a circular path. According to my invention, the weight is so mounted that when at rest, its center of gravity substantially coincides with the center of gravity of the sifter, with the result that as the weight approaches its normal or inactive position, it tends to rotate with the shaft with practically no tendency in its rotation to throw the plan sifter off center, with the result that the plan sifter is brought to rest gradually and by an even movement, and practically ceases all movement as soon as the weight comes to rest, 30 although the weight may still be rotating. Conversely, in starting, the weight will have acquired a relatively high speed of rotation, or approximately one-third of its normal speed, before it tends to move outward, with the result that 35 when it does start this latter movement, it at once throws the sifter off center instead of tending to cause it to move with it, so that in each cycle of movement thereafter, the outward throw of the weight instead of coinciding with such movement.

In the drawing—

Figure 1 is a view of my improved driving mechanism applied to a plan sifter, the supports 45 for the latter being shown broken away;

Figure 2 is a sectional plan view on an enlarged scale of the mounted weight which I employ, and

Figure 3 is a view in side elevation of the same.

Referring now to the drawing, the numeral 1 indicates a plan sifter which, as usual, is supported at its four corners by a series of wooden rods 2 from the ceiling above. Mounted on the bottom of the plan sifter is a pulley 3 which is 55

driven by means of a belt 4 passing over pulleys 5 located at one end of the plan sifter. The belt usually passes through openings in the floor and is driven from any suitable source of power. 5 Mounted in suitable bearings on the plan sifter and extending downwardly from the center of the bottom thereof is a shaft 6 on which the pulley 3 is fixedly secured. Mounted on the lower end of the shaft 6 to turn therewith is a casting 7 on 10 which is secured a rectangular metal frame 8 having side walls 9. Each of the side walls 9 of this frame is provided with a groove 10, to be hereinafter more particularly described. The numeral 11 indicates a weight provided at its inner end on either side with members 12 which, when the weight is in position as shown in Figure 2, embraces the side walls 9 of the frame 8. Secured on each of the side members 12 are two 15 stub shafts 13, 14, respectively, each of which is provided on its inner end with a roller adapted to work in the groove 10, such rollers at each side of the device being indicated, respectively, by the numerals 15 and 16. The outer ends of the shafts 13 and 14 are screw-threaded to receive nuts 17 for securing the stub shafts in position on the side members 12.

The groove 10, previously referred to, has an outer portion 18 which is curved uniformly outwardly and upwardly from its bottom, indicated at X, to its upper end, indicated at Y. From the point X the groove 10 is provided with an inward and upward curved portion 19, a substantially horizontal curved portion 20, and an upwardly curved portion 21. It will be understood that the grooves 10 in the respective side members 9 are exactly the same in formation and coincide or align with each other. The weight 11, when at rest, will have the slightly inclined position shown in Figure 1, being held in this position by engagement of the rollers 16 with the upper ends of the portions 21 of groove 10. The weight is thus in position to move outwardly when the shaft 6 is rotated. As the weight is placed in rotation, its outward movement is controlled by the movement of the rollers 15 and 16 in the groove 10, these rollers forming, as it were, fulcrums as distinguished from pivots. The movement of the weight is a compound of an outwardly sliding movement and an upward turning movement, the latter being caused by the movement of the rollers 15 and 16 in groove 10.

While the exact sequence of movements is difficult to clearly describe, a working model of the device seems to show that after being placed in rotation, the weight starts to turn outwardly, being guided by the movement of the rollers 15 in the portion 18 of groove 10 and the rollers 16 in the portion 21 of said groove. As the rollers 16 enter the portions 20 of the groove 10, the upward movement of the weight is retarded somewhat, but it is displaced further from the shaft 6. As the rollers 16 enter the portions 19 of groove 10, the rear end of the weight is now forced downwardly and the weight 11 turned outwardly on the rollers 15 as pivots, these latter rollers, however, continuing to ascend in the portions 18 of the groove 10. This continues until the rollers 16 enter the lower parts of the portions 18 of groove 10, at which time the upward movement of the weight ceases.

It will thus be seen that the upward movement of the weight, while caused by centrifugal action, is modified and controlled by the movement of the rollers 15 and 16 in the groove 10. 75 In other words, the weight is free to move out-

ward, but it is positively directed in its outward movement by the grooves 10, and the co-action between the rollers 15 and 16 and these grooves results in a positive and controlled turning movement of the weight, and this movement is so regulated that the effective power of weight, due to its momentum, is gradually applied to the plan sifter to cause its gyration and its power gradually increases to the maximum, at which time the weight is substantially in a horizontal position, as shown by Fig. 3. This gradual increase in the power of the weight is due not only to an outward and upward movement, which would occur with any suspended weight subjected to rotation, but, as will be seen, there is a bodily lateral displacement of the weight, so that when in the position of its maximum efficiency, which is the horizontal position shown in Fig. 3, the whole of said weight has been moved entirely beyond the vertical plane of the shaft 6. Owing to the operation of well known laws governing moving bodies, it will be seen that with a weight of a given number of pounds, the lateral displacement of the weight will result in greatly increasing the action of the weight on the plan sifter over what would obtain if a weight of the same number of pounds were pivoted to the shaft 6.

I have shown the best embodiment of my invention now known to me, but so far as the broad principle of the invention is concerned, I do not wish to be limited in any way to the special embodiment of the invention shown.

I wish it particularly understood that the precise form or shape of the slots 10 is not of the essence of the invention, but that any shape of curvilinear slot which will permit of an outward bodily movement of the weight and at the same time, controllably induce an upward turning movement thereof, would be within the spirit of my invention.

I claim:

1. Driving mechanism for producing gyratory movement of a suspended body, comprising a suspended weight rotatably supported on the body and capable of free bodily movement in an outward and upward direction independent thereof under power of centrifugal force, and the center of gravity of the weight when at rest substantially coinciding with the center of gravity of the suspended body, and means for rotating said weight.

2. In driving mechanism for producing gyratory movement of a suspended body, in combination with a rotatable shaft mounted on the body and means for rotating the shaft, a weight operatively mounted on said shaft but independent thereof and capable of bodily movement in an outward direction and upward movement upon a variable point of pivotal support under power of centrifugal force.

3. Driving mechanism for producing gyratory movement of a suspended body, comprising a rotatable member mounted on said body, a weight supported on said member and free to move outward under the power of centrifugal force, the support for said weight including a guide adapted to permit such bodily outward movement of the weight and to induce an upward pivotal turning movement thereof, and means for rotating said member.

4. In driving mechanism for producing gyratory movement of a suspended body, in combination with a member rotatably mounted on the body and having guiding slots, a weight slidably supported in said slots and suspended from said

member, said slots being of a formation to permit a bodily outward movement of said weight and to induce an upward pivotal turning movement thereof under the power of centrifugal action, and means for rotating said member.

5. In driving mechanism for producing gyroscopic movement of a suspended body, in combination with a member rotatably mounted on said body and provided with a groove having an inner 10 compound curve portion and an outer upward and outward curved portion, a weight having an arm provided toward its upper and lower ends, respectively, with rollers engaging in said groove, the lower roller, when the weight is at rest, normally lying at the inner end of the compound 15 curve portion of the slot and the upper roller at the beginning of said outward and upward curved portion of the slot whereby upon rotation of said member, the upper roller will move upward and outward and the lower roller will operate first to restrain and then to induce an upward turning movement of the weight, and means for rotating said member.

6. In driving mechanism for producing gyroscopic movement of a suspended body, in combination with a member rotatably mounted on 20 said body and having a curvilinear guide slot,

a weight slidably supported in said slot at an upper and lower point, whereby upon rotation of said member, the weight, under the power of centrifugal action, will be caused to move bodily and to be turned upwardly through the differential leverage afforded by the two-point engagement of said weight in said slot, and means for rotating said member.

7. In driving mechanism for producing gyroscopic movement of a suspended body, in combination with a rotatable shaft mounted on the body and means for rotating the shaft, a member fixedly secured on said shaft and having parallel side walls provided with similar and coinciding 10 slots, each slot having an outwardly and upwardly extending curved portion and an inwardly extending portion of compound curve formation, and a weight provided with suspending members having rollers located, respectively, toward the upper and lower sides of said members 15 and operating in said slots, the formation of the slots being such as to permit of an outward movement of the weight relative to said shaft and to induce an upward turning movement of the weight by differential leverage between its 20 rollers.
